UNITED STATES PATENT OFFICE.

RAINER H. KNIPPING, OF FRANKLIN, LOUISIANA.

WELL-PUMP.

1,073,143.

Specification of Letters Patent. Patented Sept. 16, 1913.

Application filed July 13, 1912. Serial No. 709,281.

To all whom it may concern:

Be it known that I, RAINER H. KNIPPING, a citizen of the United States, residing at Franklin, in the parish of St. Mary and State of Louisiana, have invented a new and useful Well-Pump, of which the following is a specification.

The device forming the subject-matter of this application is a pump designed for use in well irrigation, and adapted to operate without necessitating the forming of an accumulating pit.

The pump is so constructed that it may be slid down within the well casing, to any desired depth, section after section being added to the pump, until the desired depth is reached.

The invention aims to provide novel means for connecting the sections of the pump casing, to provide novel means for connecting shaft sections which support and operate the pumping mechanism, to provide novel means for lubricating the pumping shaft, and to provide novel means for maintaining in place, the stuffing boxes of the bearing in which the pumping shaft is journaled for rotation.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 shows the invention in longitudinal section; Fig. 2 is an elevation showing in detail the pumping element, the view illustrating the manner in which the pumping element is made effective as a means for connecting the adjacent ends of the shaft sections; Fig. 3 is a longitudinal section of the coupling which unites the sections of the casing; Fig. 4 is an end elevation of the structure shown in Fig. 3, and Fig. 5 is a side elevation of the central bearing and attendant parts.

In carrying out the invention there is provided a tubular casing which preferably is fashioned in a plurality of sections each of which is denoted by the numeral 1. Each section 1 at its lower end is threaded as in-

dicated at 3, its upper end being smooth 55 as indicated at 2. The parts 2 and 3 of the sections 1 are received within a coupling 4, provided intermediate its ends with an annular rib 5 which constitutes an abutment for the adjacent ends of the sections, 60 rivets 6 or the like being employed for the purpose of holding the smooth ends 2 of the sections 1 engaged with the coupling 4. Projecting inwardly from each of the ribs 5 are blades 7, the same being disposed in 65 inclined relation, the blades 7 supporting a central bearing 8, right and left hand threaded at its ends as shown at 9. In its interior, and adjacent its upper end, the bearing 8 is equipped with a circumscribing 70 recess 10.

Secured to the uppermost casing section 1 is a ring 11, supporting a tubular discharge chamber 12, provided with a lateral outlet 12a. The discharge member 12 supports a 75 cap plate 14. Projecting upwardly from the upper face of the cap plate 14 is a socket 15. The cap plate 14 constitutes a support for standards 16, the upper ends of which are secured to a platform 17 80 having an upstanding socket 17a, the upper end of which is enlarged to form a neck 18.

Supported within the neck 18 are cooperating ball races 19, between which are located balls 20, there being a two-part set 85 collar 21 supported by the upper of the ball races 19, the parts of the set collar 21 being equipped with flanges 22, through which are passed securing elements 23 whereby the set collar 21 is clamped about a tubular 90 shaft 24, the same comprising a plurality of sections. The upper end of the tubular shaft 24 is equipped with a funnel 25 located directly below a cock 26 carried by a receptacle 27, the receptacle 27 being supported by legs 28 which are connected with the platform 17. Rollers 29 are located within the socket 17a and carried by the bottom of the platform 17 is a gland 30 95 through which the shaft 24 passes. Secured to the shaft 24 between the platform 17 and the cap plate 14 is a pulley 31 or like element whereby rotatory movement may be imparted to the shaft 24. Located within the socket 15 are rollers 32. At this 100 point it may be stated that the rollers 32 and 29 support the shaft anti-frictionally against lateral movement, the neck 18, the

ball races 19, the balls 20 and the set collar 21 affording a thrust bearing for the shaft, preventing the shaft from moving longitudinally. The shaft 24, below the cap 5 plate 14, passes through a gland 33. As hereinbefore stated, the shaft 24 is fashioned in a plurality of sections, and as clearly shown in Fig. 2, the sections of the shaft 24 are threaded as shown at 34, to 10 engage with a hub 35, carrying inclined buckets 36. The ends of the shaft sections abut as shown at 40, within the hub 35 and, if desired, lock nuts 37 may be threaded upon the shaft sections, the lock nuts engaging the ends of the hub 35. Stuffing boxes 38 are threaded upon the portions 9 of the bearing 8 through which the shaft 24 passes, the boxes being right and left hand threaded. The boxings 38 are provided with projecting blades 39. The blades 39 slope in an opposite direction to the blades 7 which are carried by the couplings 4, the blades 39 sloping in the same direction as the buckets 30. The tubular 25 shaft 24 is equipped with a plurality of discharge ports 41, the ports being positioned opposite to and in alignment with the recesses 10 which are formed in the inner faces of the bearings 8. 30 The operation of the device hereinbefore described is as follows: When rotatory movement is imparted to the shaft 24 through the medium of the pulley 31, the buckets 36 will be rotated, and the liquid will be advanced along the casing, the liquid ultimately flowing out of the member 12^a of the discharge chamber 12. The discharge member 12^a is suitably supported in any desired manner, and through the medium of 35 the discharge chamber 12 and superposed parts, serves to support the entire weight of the pumping mechanism. A lubricant is placed in the receptacle 27, and by manipulating the cock 26, a supply of lubricant 40 may be permitted to drop into the funnel 25, the lubricant passing thence along the interior of the tubular shaft 24. When the tubular shaft 24 is rotated, the lubricant will be thrown by centrifugal force, or by 45 its inertia, more properly speaking, through the discharge ports 41 and into the recesses 10 of the bearings 8, a lubrication of the shaft 24 being thereby effected. At this point it may be noted that the engagement between the set collar 21, the ball races 19 and the neck 18 serves to maintain the discharge ports 41 opposite to the recesses 10. Owing to the fact that the stuffing boxes 38 are right and left hand threaded upon the 50 bearing 8, the tendency of the shaft 24, as it rotates, will be to force the stuffing boxes 38 more closely upon the bearing 8, thereby confining the lubricant in the bearing, and preventing the entrance of water and sand 55 into the bearing. 60

Attention is directed to the fact that the stuffing boxes 38 are equipped with blades 39, these blades 39 being located at an angle to the blades 7, and sloping in substantially the same direction as do the buckets 36. 70 When the water is advanced along the casing by the action of the buckets 26, the water will be given a rotatory movement, and when the water thus moves with a rotatory movement, the inclined blades 39 of the stuffing boxes 38 will constitute means for rotating the stuffing boxes to a firm seat, the co-operation between the buckets 36 and the blades 7 upon the one hand, and the blades 39 of the stuffing boxes 38, in the above mentioned operation, being entirely clear. 75

It will be understood that the pump herein described, is so constituted that a lubricant may be discharged readily into all of the bearings in which the shaft 24 rotates, whether such bearings be below the surface of the ground or above the surface of the ground. No matter how high a speed of rotation is imparted to the shaft 24, the stuffing boxes which are carried by the bearings will not be loosened. The pump may be lengthened to any desired extent, depending upon the depth of the well, and there are no parts in the structure which are likely to become displaced in operation. 90

Having thus described the invention, what is claimed is:—

1. In a pump, a casing having a bearing; an inclined blade in the casing adjacent the bearing; a shaft journaled in the bearing; pumping means operable by the shaft; a stuffing box threaded upon the bearing about the shaft; and a blade projecting from the stuffing box, said blade being inclined at an angle to the blade which is adjacent the bearing. 100
2. In a pump, a casing having a bearing; a shaft journaled in the bearing; an inclined bucket upon the shaft; a stuffing box threaded upon the bearing about the shaft; and a blade projecting from the stuffing box, the blade being inclined in the same direction as the bucket. 110
3. In a pump, a casing having a bearing; an inclined blade in the casing adjacent the bearing; a shaft journaled in the bearing; an inclined bucket upon the shaft; stuffing boxes right and left hand threaded upon the ends of the bearing and surrounding the shaft; and a blade projecting from each stuffing box, said blades being inclined in the same direction as the bucket and being inclined at an angle to the blade which is adjacent the bearing. 115
4. In a pump, a casing; a bearing therein; a shaft journaled in the bearing; means upon the shaft for advancing a liquid along the casing and for imparting a rotary motion to the liquid; a stuffing box threaded upon the bearing and surrounding the shaft, the 120
- 125
- 130

stuffing box being responsive to the rotary motion of the liquid.

5. In a pump, a casing; a bearing therein; a blade in the casing adjacent the bearing, the blade being inclined to impart a rotary motion to the liquid when the liquid is advanced along the casing; means upon the shaft for advancing the liquid along the casing; and a stuffing box threaded upon the 10 bearing and surrounding the shaft, the stuff-

ing box being responsive to the rotary motion of the liquid.

In testimony that I claim the foregoing as my own, I have hereto affixed my signature in the presence of two witnesses.
